(57) CLAIM

The ornamental design for a gear ring, as shown and described.

DESCRIPTION

FIG. 1 is a perspective view of gear ring showing our new design;

FIG. 2 is a top view thereof; and,

FIG. 3 is a front view thereof, the rear view being a mirror image of such front view.

The portions of the gears shown in broken lines, form no part of the claimed design.

1 Claim, 3 Drawing Sheets

FIG. 3

UNITED STATES PATENT AND TRADEMARK OFFICE
